UNITED STATES PATENT OFFICE.

WILLIAM HENRY CLARK AND LLEWELLYN JOSEPH WATTSON, OF SAN FRANCISCO, CALIFORNIA.

PEW ROPE AND LOCK.

SPECIFICATION forming part of Letters Patent No. 629,661, dated July 25, 1899.

Application filed March 10, 1899. Serial No. 708,511. (No model.)

To all whom it may concern:

Be it known that we, WILLIAM HENRY CLARK and LLEWELLYN JOSEPH WATTSON, of San Francisco, in the county of San Francisco and State of California, have invented a new and Improved Pew Rope and Lock, of which the following is a full, clear, and exact description.

The object of the invention is to provide a lock that may be made of uniform size with the rope to which it is to be applied and wherein the body and keeper of the lock will be connected by a chain extending through and preferably concealed within the rope, the chain preventing the rope from stretching.

A further object of the invention is to provide a simple yet durable form of lock and one wherein the keeper and lock may be brought automatically to a locked position, but cannot be separated without using a proper key.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is an end view of a series of pews, illustrating the application of the improved device. Fig. 2 is a longitudinal vertical section through the improved lock, said view also illustrating the manner in which chains are connected to the body and keeper of the lock. Fig. 3 is an inner face view of the body of the lock. Fig. 4 is an inner face view of the keeper or plug of the lock, and Fig. 5 is a face view of the head of the tumbler contained within the body of the lock.

A represents the body of a lock, and B the keeper or plug therefor, and both of these parts are preferably and usually made circular in cross-section. A chamber C is formed longitudinally within the body A of the lock. This chamber is in three diameters, comprising an inner section 10, an intermediate section 11, of greater diameter than the section 10, and an outer section 12, of greater diameter than the intermediate section. The chamber C is closed at the inner end of the body through the medium of a face-plate 13, secured

preferably, to the body by means of screws 14, and said screws are placed diametrically opposite each other and near the margin of the face-plate, as is shown in both Figs. 2 and 3. 55 The face-plate is provided with a central opening 15 and with recesses 16 in the wall of said opening, the recesses being shown as four in number and as located at equal distances apart. 60

A tumbler D is held to slide in the intermediate compartment or section 11 of the body-chamber C, and said tumbler D is provided with a head 17, of greater diameter than the body of the tumbler, and said head is 65 adapted to have movement in the larger section or compartment 12 of the body-chamber C, as is illustrated in Fig. 2. The inner end of the tumbler D is made to bear against a spring 18, which spring is located in the reduced compartment 10 of the body-chamber C. The tumbler is provided with a transverse recess 19, produced in one of its sides between its head and its inner end, and a keyhole slot or opening 20, produced in the 70 body A, is adapted to register with the recess 19 in the tumbler. The tumbler is also provided with a longitudinal opening 21, that connects with the recess 19 and extends through the head, registering with the opening 15 in the face-plate 13. Recesses 22 are made in the outer face of the tumbler-head, as shown in dotted lines in Fig. 3 and in full lines in Fig. 5. These recesses are located at equal distances apart and extend from the 75 opening 21 in the head of the tumbler to the periphery of said head, and the tumbler-head is further provided with two longitudinal guide-slots 23, forming continuations of two opposite recesses 22. The guide-slots 23 are 80 adapted to receive the screws or pins 14 and serve to direct the tumbler in its longitudinal movement.

The spring 18 normally holds the tumbler-head in engagement with the inner surface 95 of the face-plate 13, and the recesses 23 in the tumbler-head alternate with the recesses 16 in the face-plate. The keeper or plug B used in connection with the body A of the lock is provided with a stud 24, projected centrally 100 from its inner face, said stud 24 being of such diameter and shape that it may readily enter

the longitudinal opening 21 in the tumbler and its head, as shown in Fig. 2. A flange 25 is formed at the margin of the inner face of the keeper or plug, and said plug is adapted when the keeper is in engagement with the body of the lock to surround the outer surface of the body, as shown in Fig. 2, thus providing a neat finish. Spurs 26 are projected from the side surface of the stud 24, and these spurs are of such dimensions and are at such distances apart that when the stud 24 is introduced into the opening 15 in the face-plate of the body the spurs 26 of the stud will pass through the recesses 16 in the walls of said face-plate opening 15.

In operation when locking connection is desired between the keeper or plug and the body of the lock it is simply necessary to introduce the stud 24 and its spurs into the opening 15 of the face-plate of the body and the recesses 16 in the wall of said opening and force the two parts together until their opposing surfaces are in firm engagement, as shown in Fig. 2, whereupon the spurs 26 of the keeper will force the head of the tumbler inward, and when said spurs 26 of the keeper have reached a position between the inner surface of the face-plate 13 and outer surface of the tumbler-head either the body or the keeper of the lock may be slightly turned to bring the spurs 26 of the keeper in registry with the face-recesses 22 in the tumbler-head, whereupon the spring 18, controlling the tumbler, will carry said tumbler outward and hold the keeper firmly to the body by reason of the spurs 26 having locking engagement with the tumbler-head at its face-recesses, as shown in Fig. 2. It is impossible without absolutely breaking the lock to disconnect the body from the keeper until the tumbler of the body is forced inward, and this is accomplished through the medium of a key introduced into the transverse recess 19 of the tumbler, the key being adapted to exert inward pressure against the rear wall of said recess.

One end of a chain 27 is attached to the body A of the lock through the medium of a shank *a*, while the other end of the chain 27 is attached, through the medium of a shank *b*, to the keeper or plug B; but other means may be provided for attaching the chain to the parts of said lock. The chain is made to pass through a rope or cord 28 of suitable size and is preferably concealed therein. The ends of the rope or cord to which the parts of the lock are secured are made to fit snugly over the shanks *a* and *b*, and both the body and keeper of the lock are preferably of a diameter corresponding as nearly as possible to the diameter of the cord or rope 28.

The body A of the lock is attached to one end of a cord or rope 28 and the keeper or plug B to the opposite end of said cord or rope, as shown in Fig. 1, and the cord or rope is attached to an end of the pew E through the medium of a clamp 29, which may be of ring-like form and so attached to the pew—

through the medium of screws 30, for example—that the parts of said clamp may be adjusted to permit the rope it holds to pass readily through it until the rope or cord has been suitably adjusted, whereupon the clamp is made to hold the rope or cord firmly to the pew.

In Fig. 1 we have illustrated the ropes or cords of two adjacent pews brought together and locked. At the central portion of said Fig. 1 a rope or cord is represented as hanging loosely down from a pew, both ends of the rope or cord being free, and at the right-hand end of said Fig. 1 we have illustrated the ends of the rope or cord locked together and thrown over the top portion of the pew.

Having thus described our invention, we claim as new and desire to secure by Letters Patent—

1. In a lock, the combination, with a body, a spring-controlled tumbler mounted to slide in the said body, said tumbler being provided with a head, and a central opening in the head that extends into the interior of the tumbler, said head being provided with radial recesses in its outer face, and a face-plate for the body, having an opening registering with that in the head of the tumbler, the opening in the face-plate having recesses in its wall alternating with the recesses in the tumbler-head, of a keeper or plug provided with an extension from its inner end, adapted to enter the openings in the face-plate and tumbler-head of the body, said extension having side spurs arranged to enter the recesses in the face-plate and occupy a position between the face-plate and tumbler-head, for the purpose specified.

2. In a lock, the combination, with a body provided with a spring-controlled and key-operated tumbler, said tumbler having a head provided with marginal guide-slots, a central opening leading into a chamber in the body of the tumbler and locking-grooves radiating from said central opening, a face-plate for the body, provided with an opening registering with the opening in the tumbler-head, the wall of the opening of the face-plate being provided with recesses alternating with the locking-grooves in the tumbler-head, and fastening devices for the face-plate, that extend through the guide-slots of the tumbler-head, of a keeper or plug provided with a marginal flange adapted to embrace the body, a stud at the flanged end of the keeper, and spurs radiating from said stud, the stud being adapted to pass through the openings in the face-plate and tumbler-head and the spurs to enter the recesses in the face-plate and be received by the grooves or recesses in the tumbler-head, as set forth.

3. As a new article of manufacture, a pew-rope formed in two sections, and a lock comprising two separable parts respectively connected with the sections of the pew-rope, said parts of the lock comprising a key-controlled tumbler for removably connecting the same,

the lock and rope being of approximately equal diameters so that when the sections of the rope are joined, the several parts will present an unbroken appearance.

5 4. As a new article of manufacture, a pew-rope formed in two sections, a lock having two parts respectively joined to the sections of the pew-rope, one part of the lock comprising a stud and the other part of the lock comprising a key-controlled tumbler for holding the stud, the stud and tumbler being engaged by a relative turning movement of the sections, and the lock and rope being of approximately equal diameters so that the sections of the rope when joined will present an unbroken appearance.

5. In a lock, the combination of a chambered body-section, a keeper having a stud with spurs adapted to enter the body-section, a 20 key-controlled tumbler mounted in the body-section, a head secured to the tumbler and having slots to receive the spurs of the stud,

and a face-plate secured to the body-section and having an opening with recessed walls permitting the passage of the stud and spurs 25 through the face-plate, the openings in the head and face-plate being out of registry with each other.

6. A lock, comprising two sections, one of which is provided with a stud having a spur, 30 and the other of which is chambered to receive the stud, a face-plate secured to the said other section and having an opening through which the spur and its stud may pass, a tumbler mounted in said other section, and a head carried thereby and capable of engaging the stud and spur to hold the spur out of registry with the opening in the face-plate.
